UNITED STATES PATENT OFFICE.

FRANCESCO SKERL, OF DAYTON, OHIO, ASSIGNOR TO THE NATIONAL CASH REGISTER COMPANY, OF DAYTON, OHIO, A CORPORATION OF OHIO, (INCORPORATED IN 1906.)

TICKET-ISSUING MACHINE.

1,238,836.

Specification of Letters Patent.

Patented Sept. 4, 1917.

Application filed May 16, 1913. Serial No. 767,972.

To all whom it may concern:

Be it known that I, FRANCESCO SKERL, a citizen of Austria, residing at Dayton, in the county of Montgomery and State of Ohio, have invented certain new and useful Improvements in Ticket-Issuing Machines, of which I declare the following to be a full, clear, and exact description.

This invention relates to ticket issuing machines and more particularly to that class adapted to issue a ticket of any one of several denominations at each operation of the machine.

One of the chief sources of loss to the owners of theaters, moving picture shows, base ball grounds, parks, and the like, and also in ticket offices of elevated, subway and other railways, as well as other transportation systems and in fact wherever tickets are sold and used is the dishonesty practised by the ticket seller in reselling tickets which have been used. To prevent such dishonesty a separate ticket taker is usually employed, but it has been found that this is not always an effectual check upon the ticket seller, as the employee who collects the tickets can, by collusion with the seller, return them to the seller who can again sell them. Employment of two or more persons to prevent reselling of used tickets is, furthermore, quite an item of expense which, of course, the owners of such places wish to avoid. Various methods have been devised to prevent such dishonesty but most of them are defective inasmuch as they leave a channel by which the owner can be defrauded either by one of his employees or by the purchaser.

The principal object, therefore, of this invention is to provide a machine whereby the above losses can be eliminated as well as the expense of ticket selling employees, still retaining in use a system in which a ticket of the desired denomination can be promptly obtained by the purchaser.

It is then an object of this invention to provide a ticket issuing machine adapted to issue a ticket only when a coin of the proper value is inserted in it and more particularly to provide such a machine in which a ticket of the desired denomination can be obtained.

It is a further object of this invention to provide in a machine shown but one key

which coöperates with the inserted coins to determine the denomination of the ticket to be issued and to control the operation of the machine. The use of but one key instead of a series of keys renders the cost of construction less and simplifies the operation of the machine.

Another object of this invention is to embody in such a machine novel mechanism for printing the tickets as they are issued thereby eliminating the carrying of large numbers of valid tickets which might at any time be stolen and used.

It is, too, an object of this invention to embody in such a machine totalizing mechanism with an improved actuating device whereby the total value of the coins inserted in the machine is accumulated.

Objects of the specific construction disclosed are to provide means for preventing the operation of the machine until the coin is inserted, for locking the key in its depressed position, and for retaining the coin in its coöperative position until the end of the operation of the machine.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Figure 1 is a left side elevation of a machine embodying the present invention with the cabinet removed and showing the operating gearing for the machine.

Fig. 2 is a fragmentary right hand side elevation of the machine shown in Fig. 1, with the side of the cabinet removed.

Fig. 3 is a detailed view taken along the key and the sliding plates operated thereby and shows part of the mechanism controlled by the coöperation of the key and the coins inserted in the machine.

Fig. 4 is a detailed view of the totalizer.

Fig. 5 is a detailed view showing the key and the devices actuated by the key and employed to lock the key, unlock the machine and to differentially position the type carrier and totalizer actuating racks.

The specific embodiment of the invention

shown in the drawings is illustrated only as the invention is clearly applicable to other types of vending machines. This invention as shown is applied to a ticket issuing machine intended when in use to be suitably placed so that the customer may insert the proper coin and subsequently operate the key and thereby secure a ticket of the desired denomination, the opening through which the tickets are delivered being located on top of the machine as are the slots and the key.

The machine is equipped with a single key and a number of coin slots, one for each ticket of a different denomination and to operate the machine the purchaser need only insert his coin into the proper slot and press the key, the machine then automatically printing and issuing a ticket of the desired denomination and operating the accounting device according to the value of the ticket.

The coin slots are so positioned that when a coin is inserted into the machine it constitutes a connection between two plates, one of which upon depression of the key is given a variable extent of movement dependent upon the value of the coin. Slot closing flanges are carried by the latter plate so that when the plate is moved the slots are closed against another insertion of a coin during the operation of the machine. The differential movement of this latter plate is imparted to a notched segment arm and further depression of the key rocks a member into alining position with the notches and also controls the actuation of the locking device for the key. The notched segment arm is connected to members employed to actuate the accounting device and the type carriers so that when the segment arm is moved its differential movement is imparted to the actuating members. Mechanism driven by a motor operates the ticket feeding mechanism and printing mechanism. rocks the totalizer into engagement with its actuating member, and finally restores the actuating members to initial position and renders the key locking and the slot closing mechanism ineffective.

The above description briefly points out the general features of construction of the machine. The details appear from the drawings wherein 1 (Fig. 1) is a shaft which is to be given two complete rotations at an operation either manually by a crank handle or from a motor. The motor or crank handle are not shown in the accompanying drawings but it is to be understood that one of numerous types of motor mechanisms can be employed and particular reference may be made to that shown and described in Letters Patent of the United States, No. 923,857, granted June 8th, 1909, upon application filed by C. F. Kettering, as the connections between the motor and the operating

mechanism as well as the clutch connections are peculiarly adapted to control and operate the machine herein shown.

Fast to the shaft 1 is a gear 2 which meshes with a gear 3 fast to the main drive shaft 4 supported by bearings in the side frames 5 and 6 of the machine. A large gear on the stub shaft 280 supported by the side frame 6 is intermediate and meshes with the gear 3 and also gear 8 which is fast to another shaft 9 also loosely journaled in the sides of the frames 5 and 6. The various operative mechanisms disclosed herein are actuated through one rotation of the shafts 4 and 9 brought about by two rotations of the driving pinion 2 and the connections between these mechanisms and these shafts will be taken up in detail in the description of the mechanisms.

The complete depression of a single key coöperating with the coin inserted in the machine differentially sets the actuating racks for the type carriers and the totalizer, releases the motor locking lever, and actuates the device which locks the key in its depressed position until the end of the operation of the machine. The key and the coin slots and the sliding plates, actuated by the coöperation of the key with the inserted coins, through which the above mentioned functions are accomplished, are shown in Fig. 3 and will now be described. A lever 10 is centrally pivoted to a key 11 by a pin 12 and carries a pin 13, projecting laterally from the right hand end of this lever and passing into an elongated slot 14 formed in an arm 15 of a bell crank pivoted by a pin 17 to the frame 16 suitably supported by the frames of the machine. The other arm 18 of this bell crank is constructed to form a segment arm which has one curved notch 19 in the upper portion of its periphery. A plate 20 is pivoted to a projection on the arm 15 by a pin 21 and carries pins 22 which project into slots 24 in a plate 23 which also has similar pins 25 projecting into similar slots 26 in the plate 20. The plates 20 and 23 are parallel to each other and adjacent to the coin slots 23^a, 24^a, and 25^a, which represent the five, ten and twenty-five cent slots respectively and the distance between the plates is slightly greater than the thickness of a quarter so that the inserted coin can drop between them. Both of these plates at their rear ends are pivoted to similarly shaped arms 27 which are pivoted at 28 to the frame 16 and connected at their lower ends, to one end of springs 29 which are under tension between these arms and the dog 30 mounted at 30° and thereby tends to hold the plates in the position, shown in Fig. 3. The plate 23 is pivoted by a pin back of pin 21 (Fig. 3), to an arm 31 of a bell crank which in turn is pivoted at 32 to the frame 16. The other arm 32 of

this bell crank is constructed similarly to the segment arm 18 but has three similarly shaped notches 33, 34 and 35 in its periphery; the last of which normally coincides 5 with the notch in the arm 18.

The left hand end of the lever 10 carries a pin 36 which projects into a slot 37 in an arm 38 of a lever loosely mounted on a rod 39 which projects from the frame 16. The 10 other arm 41 of this lever projects downwardly and carries a pin 41^a which is normally in operative relation with the lower parts of the peripheries of the segment arms 18 and 32. A spring 40, which is 15 under tension, extends from the pin 40^a on the frame 16 to an arm 42, which is integral with the arms 38 and 41. The coins are inserted through the slots 23^a, 24^a and 25^a which represent the five, ten and twenty-five 20 cent slots respectively, as stated, and drop in front of and into engagement with the corresponding pins 22 projecting from the plate 23. Each of the pins 22 and 25 has a curved face of the same radius as the coin 25 with which it engages. The coins are prevented from passing into the guideway 46^a to the coin receptacle 47^a (Fig. 1), by flanges 46 (Fig. 3) upon which the coins rest when inserted into the machine. These 30 flanges project laterally from the upper edge of a plate 47 slidably mounted on the frame 16 by slot-and-pin connections. Toward the end of an operation of the machine the plate 47 is forced rearwardly by 35 the lever 48 and the inserted coin is permitted then to pass to the coin receptacle. The upper end of the lever 48 is in engagement with a lug 49 projecting downwardly from one of the flanges 46 and this lever is 40 rocked to move the plate 47 rearward by the engagement of the lower end of the lever with an anti-friction roller 1000 projecting laterally from a cam 141 fast on the shaft 9. After the roller 1000 has moved out of 45 engagement with the lever 48, the spring 50 which is under tension between the arm 38 and the plate 47 restores the plate 47 and the lever 48 to their initial positions.

The operation of these devices so far described is as follows: When the key 11 is depressed the pin 36 being held in operative relation with the upper end of the curved slot 37 serves as a pivotal center for the lever 10, as the lever of which 38 and 41 are arms, is not permitted to rock about its pivotal center 39 because of the normal engagement of the pin 41^a on the arm 41 with the peripheries of the segment arms 18 and 32. Movement of the lever 10 about 55 the pivot 36, however, through the connection of the other end of the lever with the bell crank of which 15 and 18 are the arms, serves to rock this bell crank an invariable distance which is sufficient to carry the 60 notch 19 opposite to the pin 41^a on the arm 65

41. The plate 20 being connected at 21 to this bell crank has imparted thereto a like invariable extent of movement forwardly in the direction of its length as the pin 13 can move from the forward part to the rear 70 part of the slot 14 in the arm 15. When a quarter has been inserted the plate 23 is to be moved the same distance as the plate 20 upon the depression of the key, as the normal distance between the pins 22 and 25 on 75 the detents 20 and 23 which coöperate with inserted quarters is equal to the diameter of a quarter and therefore the other segment arm 32 being an arm of a bell crank lever connected to the plate 23 is rocked about 17 80 as a pivot to the same extent as the segment arm 18 is rocked thus preserving the normal coincidence of the notches 19 and 35 in the arms 18 and 32 respectively. The normal distance between the pins 22 and 25, which 85 project from the plates 20 and 23 and are to engage a dime inserted into the ten cent slot, is such that the plate 20 and therefore the segment arm 18 are given three steps or units of movement before the distance between the pins is reduced to the diameter of the coin after which the segment arm 32 is given two units of movement since the plate 23 to which this segment arm is pivoted is moved with the plate 20 during the last two 90 steps of movement of the latter, the extent of the invariable movement of which is the same as an excursion of five units of movement of the plate 23. This initial movement of three steps of the segment arm 18 100 brings the notch 19 in this arm into coincidence with the notch 34 in the segment 32 at the end of the third step of movement of the arm 18 and this coincidence is preserved during the two steps of movement of 105 the arm 32 and the last two steps of movement of the arm 18 as the arms are then moving together. The normal distance between the pins 22 and 25 which are to engage a nickel dropped into the five cent slot 110 is such that the segment arm 18 is given four steps of movement upon the depression of the key before the notch 19 in the arm 18 is brought into coincidence with the lowest notch 33 in the arm 32 after which the arm 18 is moved one step farther and the coincidence of the notches is preserved during 115 this last step of movement as the coin constitutes a connection between the plates, and the arm 32 is moved therefore one step with 120 the arm 18 after the notches are brought into coincidence.

The plate 23 at its upper edge carries horizontally projecting flanges 52 which, when the detent is moved, as explained, 125 close the slots 23^a, 24^a, and 25^a and hence prevent the insertion of another coin into the slots during that operation of the machine. After the segment arm 32 has been differentially positioned, further depression 130

of the key is permitted. As the roller 41^a is then in operative relation with the coinciding notches on the segment arms 18 and 32 and can be moved by further depression 5 of the key into said notches after which it is held in such position by the engagement of the pin 36 with the lower part of the slot 37.

The devices actuated by the key 11 and employed to lock the key in its depressed position shown in Fig. 5 will now be described. A link 53 is pivoted at its upper end to the arm 42 by the pin 54 and has at its lower end a slot 55^a into which a pin 55 projecting from an arm 56 passes. The arm 15 56 is integral with the arms 57 and 58 which are loosely mounted on a stub shaft 59 projecting from the frame of the machine. The plane face of a lug 60 which projects from the arm 58 is normally in engagement with the upper edge of a projection 61 on the forward end of a lever 62 which is fast to a shaft 63 supported by bearings in the side frames of the machine. An arm 64 is loosely mounted on the arm 56 by the pin 55 and at 20 its upper end has two shoulders 65, the upper one of which is normally held in engagement with the plane face of the stud 66, projecting from the link 53, by the spring 67 which is under tension between the arm 58 and the lower end of arm 64. One arm 68 of a bell crank pivoted to the frame 16 of the machine by the rod 39 carries a hooked shaped projection 69, while the other arm 68^a has pivoted at its outer end a link 70 which, at its lower 25 end, is connected to the rear end of the lever 62 by the pin 71.

When a coin is inserted into its proper slot and the key 11 depressed, the arm 42 is rocked about its pivotal center 39, as has 30 been explained and the lug 60 is taken out of engagement with the projection 61 by the rocking of the arm 58 through the link 53, and the arms 56 and 64. The lever 62 is then 35 rocked in a counter-clockwise direction by a tensioned spring 72 secured at its ends to the lever 62 and to the frame of the machine, and the upper face of the projection 73 of the lever 62 is carried into engagement with the lug 60. At the same time the hook 40 shaped projection 69 on the arm 68 passes over a pin 74 projecting laterally from the lever 10 which is then in lowered position and thereby holds the key in its depressed 45 position.

55 The key is not released until the end of the operation of the machine but as the operating mechanism releases the key through the parts just described as being employed to lock the key in depressed position this operation may be described here. A disk 75, journaled to the drive shaft 4 is revolved in a clockwise direction, (Fig. 5), and carries three laterally projecting studs 76, 77, and 60 78. The stud 76 toward the end of each operation of the machine engages the inclined

face 79 of an arm 80 fast to the shaft 63 and rocks the lever 62 against the action of the spring 72 to its initial position and thereby takes the hook 69 on the arm 68 out of operative relationship with the stud 74. Immediately thereafter the stud 78 engages an inclined face 81 of a projection 82 on the arm 64 and forces the upper shoulder 65 of the arm 64 out of engagement with the lug 66 on the link 53. The rocking of the arms 56, 57, and 58 to initial position by the spring 67 is then permitted, with the key remaining in its depressed position, as the pin 55 on the arm 56 by reason of the upper shoulder 65 of the arm 64 having been thrown out of engagement with the pin 66, can be moved out of engagement with the lower end of the slot 55^a in link 53 into engagement with the upper end of the slot, but to make such return movement of the arms 56, 57, and 58 positive the arm 57 is provided with a projection 84 having an inclined face 85 so that the stud 78 will engage this face after the upper shoulder 65 is carried out of engagement with the lugs 66, and thereby positively restore the lug 60 on the lever 62 to its normal locking position over the projection 61 on the lever 62. The restoration of the lever 62 to its normal locking position rocks the hooked end 69 of the arm 68 out of operative relation with the roller 74 on the lever 10 and thereby releases the key. After the key is released it is restored to normal position by the spring coiled about its shank and the spring 40 raises the link 53 and brings its projection 66 opposite the upper shoulder 65 of the arm 64 which arm is then rocked by its spring 67 to carry its upper shoulder 65 below and into engagement with the lug 66. This raising of the link 53 to normal position 105 also brings the lower end of the slot 55^a into engagement with the pin 55 carried by the arm 56.

The releasing of the motor employed to drive the operating mechanism is effected 110 through the rocking of the lever 62 by the depression of the key as just explained and the connections between the motor and this lever are shown in Figs. 1 and 5. An arm 86 is fast to the shaft 63 and is connected at 115 its outer end by a pin 86^a to a link 87 which at its upper end (Fig. 1) is pivoted at 88^a to the motor locking lever 88. The rocking of the lever 62 upon depression of a key as has been explained, lowers the arm 86 and thereby releases the motor through the rocking of the projection 89 of the lever 88 out of engagement with the clutch members of the motor. At the end of the operation of the machine the rocking of the lever to its 125 initial position, as has been explained, restores the lever 88 to its locking position until the next operation of the machine. Simultaneously with the rocking of the motor locking lever 88 out of engagement with the 130

clutch members the motor circuit is closed. This is accomplished by movement of a clutch member under spring action rocking an arm to force contact strips to close the 5 circuit. This circuit closing device is not shown in the accompanying drawings but reference is made to the aforesaid patent of C. F. Kettering.

The third function of the key, through its 10 co-operation with the coin, is to position differentially the actuating racks for the type carrier and the totalizer. To this end connections between the segment arm 32 and the racks are provided and these connections 15 may now be taken up in detail. A link 96 (Fig. 5) has a notch 97 on the lower edge of its forward end, which normally straddles a pin 98 projecting from the segment arm 32 and the other end of this link is pivoted at 20 99^a to the outer end of an arm 99 which is fast to a shaft 100 supported by the side frames 5 and 6 of the machine. A projecting arm 101 on this link carries at its outer end a roller 102 which projects into a 25 slot 103 in an irregularly shaped plate 104 pivoted on a rod 105. Fast to the shaft 100 is a lever 105^a (Fig. 2), one arm 105^b of which is a segmental actuating rack for the totalizer elements 106 which are employed 30 to accumulate the value of the coins inserted into the machine and which are loosely mounted upon the shaft 107. The other arm 108 of this lever is connected at 109^a to a link 109 which, at its other end, is pivoted at 110^a to an actuating rack 110 loosely mounted on a stub shaft 111 projecting from the side frame 5 of the machine. The actuator rack 110 meshes with a pinion wheel 113 loosely mounted on the shaft 114, supported by the bars 115 pivoted at 115^a to the side frame 5 of the machine, but integral with the type carrier 117, carrying three types 118, 119 and 120 adapted to print a 45 5¢, 10¢ and 25¢ character respectively.

The totalizer elements 106 which are loosely mounted on the shaft 107 are constructed similarly to those shown and described in the present applicant's application, Serial No. 776,054, filed May 7, 1913. 50

The registering wheel of lowest order is actuated directly by the engagement of teeth of actuating arm 105^a with the pinion 116 integral with the wheel and is provided with alternate ciphers and fives and is arranged to transfer to the wheel of the next highest order at each second unit of movement, the wheels of higher order transferring after each complete rotation. Carrying operations from wheels of lower order to wheels 55 of higher order are accomplished by the well known Geneva stop mechanism, as indicated in Fig. 4.

The counter elements 124 employed for 60 registering the number of operations of the machine are loosely mounted on the shaft

124^a. The shafts 107 and 124^a which support the totalizer and the counter are carried by the auxiliary frame 126. This frame is constructed of one plate of metal and is pivoted to the frame 5 of the machine by 70 the rod 128 and is free to swing vertically in the opening 1285 of the main frame 5. The left hand side of this auxiliary frame is all in the same vertical plane and forms a right angle with the top of the frame. The 75 portion 127^a of the right side of the frame is parallel to the left side of the frame and supports the right hand end of the shaft 107. The portion 126^a of the right side of the frame is also parallel to the left side but 80 is not in the same vertical plane as is the portion 127^a the distance between the left side of the frame and the portion 126^a being less than that between the left side and the portion 127^a. The portion 126^a supports the right end of the shaft 124^a which 85 carries the counter elements employed to register the number of operations of the machine, and the distance between the portion 126^a and the left side of the auxiliary frame 90 is less than that between the portion 127^a and the left side because there are fewer counter elements on the shaft 124^a than there are totalizer elements on the shaft 107, as the elements on the shafts 107 are to register larger amounts than those on the shaft 124^a.

The counter elements on the shaft 124^a are actuated by the engagement of the graduated tines 129 arranged in a manner well known in the art, on the common pawl 130, with the ratchet wheels 131, one of which is integral with each registering wheel, whereby when one wheel is given complete rotation the wheel of next higher order is moved one 100 notch. This pawl 130 is mounted on the frame 5 of the machine by the pin 132 and the tines 129 are kept in engagement with the ratchet wheels 131 by the spring 133. As 105 this device is one so well known on the market it need not be described in further detail.

After the actuating rack 105^b has been differentially positioned, as explained, the pinion 116 which is integral with the totalizer 115 wheel of lowest denomination is rocked into mesh with the teeth of the segment rack through a pitman 142 which, at its upper end, is pivoted at 1271 to the frame portion 126^a and at its lower end is forked over the 120 drive shaft 9 and carries an anti-friction roller 143 riding in a cam groove 144 in the face of a disk 145. The shape of this cam groove 144 is such that the pitman 142 is given a reciprocating movement upon each 125 operation of the machine and thereby rocks the frames 126 and 127 about their pivotal centers 128 so that the pinion 116 is thrown into engagement with the rack 105^b. The counter mounted upon the shaft 124^a has 130

"one" added to the previous amount on the totalizer, each time the frames 126 and 127 are rocked downward, by the engagement of the counter with the pawl 130. The link 96 because of the engagement of the roller 102 on the arm 101 in the slot 103 in the plate 104 is then rocked upward out of engagement with the pin 98 through the engagement of the pin 77 on the disk 75 with the cam face 146 of the irregularly shaped plate 104 and the upper edge of the arm 96 is thereby raised into contact with the dog 30 so that after the actuating racks and the link 96 are restored the dog will engage the shoulder 147 on the link 96 and prevent the link from moving backward so that when the segment 31 is restored to normal position the recess 97 can again engage the pin 98. A roller 148 projects from the arm 108 and is so positioned that open cam 149 fast to the rotation shaft 9 engages the roller 148 toward the end of the operation of the machine but after the link 96 is disconnected from the pin 98 and restores the actuating rack 105^a to normal position while the totalizer pinion 116 is in engagement with the teeth of the segment 105^b. During this restoration of the actuating rack the pin 98 enters the recess between the link 96 and the arm 101. It is therefore seen that upon every operation of the machine the value of the coin inserted into the machine is accumulated upon the totalizer when the actuating rack is restored to normal position. The plate 23, and therefore the segment arm 32 are restored to their normal position by the spring 29 connected to the dog 30 and the arms 27 which support the rear end of the plate. Finally the link 96 is lowered to its initial position so that the recess 97 again engages the pin 98 on the segment arm 32 as the irregularly shaped plate 104 is given a return movement when the pin 77 passes out of engagement with the curved face 147^a of this plate by the engagement of a pin 285 projecting from the link 53, with the lower edge of the forward end of an arm 143^a integral with the plate 104, while the link 53 is being restored to normal position.

After the type carrier has been positioned to print on the paper strip 150 the denomination of the desired ticket the ticket printing and issuing mechanism are actuated by the motor. A gear 153 is journaled on the main drive shaft 4 and meshes with a gear 154 integral with the feed roll 155. This latter gear in turn meshes with a gear 156 movable with the impression roller 158. The inking roll 159 is employed to ink the type of the dater 160 and of the consecutive numbering device 161, which devices are employed to record the date and the consecutive number on the ticket and being old in the art and not essential to the understanding of the invention need not be de-

scribed in detail. A platen frame 162 is loosely mounted on the shaft 4 and at its upper end carries a platen 163. This platen carrying frame 162 has an anti-friction roller 164 riding in a cam groove 165 constructed in the face of the impression roller 158. The configuration of this cam groove is such that the platen is given an invariable extent of movement against the type carriers upon each operation of the machine and before the ticket is fed into the opening 166^a, surrounded by the guard 166 on the top of the cabinet of the machine, by the engagement of the flanges 167 on the feed roll 155 with the periphery of the cylinder 158 which construction is also well known in the art. A slidable plate 168 which is connected to the type carrier supporting frame 115 by slot and pin connections is also attached to the platen carrying frame 162 by the pin 169 engaging in the slot 170 and upon each movement of the platen carrying frame 162 the projection 168^a, on the sliding plate enters one of the notches 169^a in the plate 170^a integral with the type carrier 117 and thereby alines the type carriers while an impression is being taken therefrom on the paper strip 150. A spring pressed pawl 173 which engages with the teeth of ratchet wheel 171 integral with the ribbon feed roll 172, is pivoted at 1731 on the sliding plate 168, and 174 designates a pawl employed to prevent backward rotation of the roll 172. Upon the return movement of the platen frame 162 and therefore of the sliding plate 168 after the ticket is printed, the pawl 173 engages the next tooth of the ratchet and feeds the inking ribbon 175 one step. This inking ribbon is of the continuous type and passes around the anti-friction roller 302, up between the printing platen and type over the guide 3003, beneath the tension device 181, around roll 300, roller 302, and between the feeding roll 172 and the inking roll 176. The ribbon is inked by the inking roll 176 which is carried by a frame 177 pivoted to the frame 5 of the machine, by the rod 178, and kept in engagement with the feeding roll 172 by means of the spring 179 under tension between the frame 177 and the pin 177^a projecting from the frame 6. The roll 180 supported by the arms 181 which are pivoted to the frame 5 of the machine at 181^a, is employed to tension the inking ribbon 175.

After the denomination of the ticket has been printed and it has been fed far enough into the opening 166^a in the cabinet by the feed rollers 155 and 158 so that it may be withdrawn by the fingers, it is severed by knife edges 184 and 185. The upper knife blade 184 is actuated through the engagement of the roller 186 in the cam groove 165, the roller being carried by the lower arm of the lever 187 pivoted at 188 to the frame 5

of the machine and the knife blade is kept into engagement with a block 189 by means of a spring 190 which presses against the arm 191, carrying the knife 184. The wire 5 clips 192^a guide the ticket as it is fed and the wire clip 192 and the guide plate 192^b prevent it from falling into the operating mechanism and retains it in a nearly vertical position. After the ticket has been issued 10 the actuating rack 110 is restored to initial position through the engagement of the open cam 149 with the roller 148, as has been fully described.

The device employed to turn the totalizer 15 wheels 106 to zero position is well known in the art, and in general consists of the intermeshing gears 134 and 135 fast to the left end of shafts 107 and 124^a respectively, so that when the key is inserted into the key 20 seat 136 and turned, the shafts carrying both sets of registering wheels are turned through a small bevel gear on the shaft 124^a meshing with a small bevel gear on the lock 216. Interposed between the several registering 25 wheels on the shafts 124^a and 107 are pawls suitable to pick up the wheels at different points at which they may be standing and return them to zero position as these shafts are rotated. A disk 137 is fast on the shaft 30 107 and when the shaft is rotated the pin 138 on the arm 138^a, pivoted at 140^a is forced out of normal engagement with a notch in the disk 137 and the curved end 139^a of the pawl 134, which has a slot 142^a through 35 which the stub shaft 140^a passes, and is connected to the arm 138^a by a spring coiled about the stub shaft 140^a, is rocked into the path of a pin 140 projecting laterally from the disk 137 so that when the wheels are restored 40 to zero position the pin 140 abuts the end 139 and prevents further rotation of the wheel. The pawl 139 is then returned to its initial position through the action of the spring coiled about the stub shaft 140^a.

45 The operating mechanism is restored the last few degrees to normal position by the engagement of the anti-friction roller 193 with the nearly radial face 194 of the open cam 141, the roller being carried by the lever 195 which, at its lower end, is secured to a highly tensioned spring, 224, (Fig. 1). This device is old in the art and is employed as the motor may not bring the operating parts completely home.

50 The complete operation of the machine is effected by merely inserting the coin and subsequently depressing the key 11. The initial movement of the key, because of the engagement of the pin 41^a on the arm 41 with the peripheries of the segment arms 18 and 32, rocks the lever 10 about the pin 36, as a pivotal center and the plate 20 through the arm 15, connecting it with the lever 10, is given an invariable extent of movement, 55 which is generally transverse to that given

the key. The segment arm 18 is thereby rocked so that its notch 19 is adjacent to the pin 41^a, but further depression of the key 11 is prevented, if no coin has been inserted into the machine through one of the coin 70 slots, by the engagement of the pin 41^a with the periphery of the segment arm 32. When a nickel, dime or quarter has been inserted into the proper slot, the arm 32 is given one, two or five units of movement respectively 75 by the initial movement of the key 11, through the engagement of the pins 22 and 25 on the plates 20 and 23 with the coin, and further depression of the key is permitted as the pin 41^a enters into alining position 80 with the coinciding notches on the segment arms 18 and 32. Final movement of the key 11 permits the lever 62 to be rocked in a counter-clockwise direction by the spring 72, as the lug 60 is taken out of engagement 85 with the projection 61 of the lever 62 through the link 53 and the arms 64, 56, and 58, and thereby the hook 69 on the arm 68 is brought into latching position over the pin 74 through link 70 and the arm 68^a and 90 the lower projection 73 of this lever 62 is brought into engagement with the lug 60. The motor locking lever 89 is taken out of its locking position at the same time as the arm 86 to which the lever 89 is secured by 95 the link 87 is fast to the shaft 63 and is therefore rocked when the lever 62 is rocked.

The differential movement of the segment arm 32 is imparted to the totalizer actuating rack 105^a through the link 96, the arm 99, 100 and the shaft 100 and to type carriers through these same arms and shaft and the arm 108 and the link 109. The rotation of the disk 145 through the operation of the anti-friction roller 143 on the pitman 142 105 rocks the frame 126 about its pivotal center and the pinion 116, integral with the units wheel of the totalizer, is thereby brought into mesh with its actuating rack 105^b and the counter elements, which record the number 110 of operations of the machine, are actuated upon the rocking of this frame through the graduated teeth 129 on the pawl 130.

The platen 163 is given an oscillatory 115 movement of invariable extent about the shaft 4 and is brought into contact with the type on the type carrier 117 through the co-operation of the roller 164 in the cam groove 165 whereby the ticket of the value of the 120 inserted coin is printed. Upon the return movement of the platen carrying frame 162 the inking ribbon 175 is fed one step through the engagement of the pawl 173 mounted on the slidtable plate 168 with the teeth of the 125 ratchet wheel 171 which is integral with the feed roll 172. The flange 167 on the feed roll 155 then feeds the paper 150 the distance of one ticket and the ticket is subsequently severed by the knife edges 184 130

and 185, the knife edge 184 being actuated through the cam groove 165 in which the roller 186 on the lever 187 rides. After the denomination of the ticket has been printed 5 the open cam 149 engages the roller 148 on the lower end of the lever 105^a and restores the type carrier and totalizer actuating racks to normal position and the totalizer elements are then rocked out of engagement 10 with the pawl 130 and the rack 105.

At the end of the operation of the machine the engagement of the stud 76, projecting from the disk 75, with the cam edge 79 of the arm 80 rocks the lever 62 to its normal 15 position whereby the hook 69 is taken out of operative relationship with the pin 74 projecting from the lever 10 and the motor locking lever 88 is returned to its locking position. The stud 78, at the very time that the 20 lever 62 is restored to its normal position, forces the upper shoulder 65 of the arm 64 out of engagement with the lug 66 permitting the link 53 to rise, and the lug 60 is finally brought into engagement with the 25 upper edge of the projection 61 on the lever 62 by the engagement of the stud 78 with the inclined face 85 of the projection 84 of the arm 57, whereby the lever is locked until the next operation of the machine.

30 While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the 35 claims which follow.

What is claimed is:

40 1. In a machine of the class described, the combination with a main operating mechanism; of coin receptacles; a ticket issuing mechanism adapted to issue tickets of different denominations and including a movable member whose position determines the 45 denomination of the ticket to be issued; and manipulative means coöperating with coins placed in the receptacle to differentially position said movable member.

50 2. In a machine of the class described, the combination with a ticket issuing device adapted to issue tickets of different denominations; of operating means therefor; coin receptacles; and manipulative means coöperating with coins inserted into said receptacles to determine the denomination of the 55 ticket to be issued by said device.

3. In a machine of the class described, the combination with a ticket issuing device 60 adapted to issue tickets of different denominations; operating means therefor; a series of coin receptacles; and a single manipulative device coöperating with coins inserted into the receptacles to determine the de-

nomination of the ticket to be issued by said 65 device.

4. In a machine of the class described, the combination with a ticket issuing device adapted to issue a ticket of one of several denominations; of operating means therefor; a series of coin slots and a single manipulative device coöperating with coins inserted into the slots for controlling said issuing device and said operating means whereby said operating means causes said 75 ticket issuing device to issue a ticket of the same value as the coin inserted into the machine.

5. In a ticket issuing machine the combination with a ticket issuing device adapted 80 to issue tickets of different denominations; of a series of coin slots; a manipulative device coöperating with the coins inserted into said slots and a member differentially positioned by the manipulative device; and connections between said member and said issuing device whereby the differential movement of the member determines the value of the ticket to be issued.

6. In a machine of the class described, the combination with a printing mechanism including a type carrier; of actuating means for differentially positioning said type carrier; coin receptacles; and manipulative means coöperating with coins inserted in 95 the receptacles to cause said actuating means to differentially position said type carrier.

7. In a machine of the class described, the combination with a printing mechanism including a type carrier to be differentially 100 positioned; of coin receptacles; and manipulative means coöperating with coins inserted into the receptacles to differentially position the type carrier.

8. In a machine of the class described, the 105 combination with a printing device, including a type carrier; of a member to be differentially positioned; a series of coin slots; a manipulative device coöperating with the coins inserted into said slots for differentially positioning said member; and connections intermediate said member and said type carrier whereby said differential movement of said member is imparted to said 110 type carrier.

9. In a machine of the class described, the combination with a printing device, including a type carrier; of a manipulative device; a series of coin slots; a member differentially positioned by the coöperation of the manipulative device with coins inserted into said slots; connections intermediate said member and said type carrier whereby the differential movement of said member is imparted to said type carrier; and operative means for rendering said connections ineffective after said type carrier has been 125 differentially positioned.

10. In a machine of the class described, the combination with a printing mechanism including a type carrier; of a manipulative device; a series of coin slots; a sliding member bearing projections and given a movement of invariable extent by said manipulative device; a second sliding member bearing projections coöperating with the projections on the first sliding member to engage a coin inserted in one of said slots whereby said second member is through the coin differentially positioned upon movement of the sliding member; and connections intermediate said type carrier and the second member whereby the differential movement of the second member is imparted to said type carrier. 65
11. In a machine of the class described, the combination with a type carrier; of an actuating rack therefor; an accounting device; an actuating rack therefor; a series of coin slots; a manipulative device coöperating with coins inserted into the slots; a member given an extent of movement by said manipulative means dependent on the value of the coin inserted; and connections intermediate said racks and said member whereby said racks are differentially positioned upon movement of said member. 70
12. In a machine of the class described, the combination with an accounting device; of a printing mechanism including a type carrier; receptacles for the insertion of coins; and connections between the receptacles, accounting device and printing mechanism, whereby coins inserted into said receptacles may determine the entering of amounts in the accounting device and the setting of the type for the printing mechanism. 75
13. In a machine of the class described, the combination with an accounting device; of an actuating rack therefor normally out of engagement therewith; a printing mechanism including a type carrier; coin receptacles; a single key coöperating with the coins inserted into the receptacles for differentially positioning said actuating rack and said type carrier in correspondence to the value of the coins inserted; operating mechanism constructed to engage the actuating rack with the accounting device and to return to normal position the actuating racks, whereby the value of the coins inserted into the receptacle is entered on the accounting device; and connections from said operating mechanism for actuating the printing mechanism whereby an impression of the amount entered on the totalizer may be taken from said type carriers. 80
14. In a machine of the class described, the combination with an accounting device, of a printing mechanism including a type carrier; coin receptacles; and manipulative means coöperating with the coins inserted into the coin receptacles for controlling the entering of the value of coins upon the accounting device and for positioning the type carrier so that each amount entered on the accounting device can be recorded on record material. 85
15. In a machine of the class described, the combination with a ticket supply roll; of printing and severing mechanism including a type carrier for printing and severing tickets from said supply roll; a coin controlled manipulative device for positively positioning said type carrier; and operating means for said printing and issuing mechanism. 90
16. In a machine of the class described, the combination with a ticket issuing mechanism adapted to issue tickets of different denominations and including a type carrier; of operating means therefor; a plate; a series of coin receptacles; a manipulative device coöperating with the coins inserted into said coin receptacles to give the plate a differential movement; and connections intermediate said plate and said type carrier whereby the type carrier is so positioned that an impression of the value of the coin may be made on the ticket to be issued. 95
17. In a ticket issuing machine, adapted to issue tickets of different denominations, the combination with a manipulative device; of a plate given an invariable extent of movement thereby; a series of coin slots; and a second plate connected to the first plate by a coin inserted into one of the slots whereby said second plate is differentially moved when said first plate is moved, said differential movement determining the denomination of the ticket to be issued. 100
18. In a machine of the class described, the combination with a member to be differentially positioned; of a manipulative device capable of being given but one effective extent of movement; a series of coin receptacles; an element actuated by said manipulative device and controlled by the coin inserted into one of said receptacles; and connections intermediate said element and said member whereby the effective extent of movement of said manipulative device differentially positions said member. 105
19. In a machine of the class described, the combination with a ticket issuing mechanism adapted to issue tickets of different denominations; of operating means therefor; a series of coin slots; a sliding member for determining the denomination of the ticket to be issued; and manipulative means coöperating with a coin inserted into one of said slots for differentially positioning said sliding member whereby the denomination of the ticket to be issued is determined. 110
20. In a machine of the class described, 115

the combination with a ticket issuing mechanism adapted to issue tickets of different denominations; of operating means therefor; a locking device for said means; a manipulative device; a member given an invariable extent of movement by said manipulative device; coin receptacles; and a second member given a variable extent of movement by said first member dependent upon the 10 value of the coin inserted into one of said receptacles, and constructed to render the locking device ineffective and determine the denomination of the ticket to be issued.

21. In a machine of the class described, 15 the combination with a differentially movable actuating element; of a manipulative device; a member given an invariable extent of movement by said manipulative device; a series of coin receptacles; a second member 20 connected to the first member by a coin inserted in one of the receptacles; and connections intermediate said second member and said actuating element whereby movement of said first member, when a coin is inserted, 25 differentially positions said actuating element.

22. In a machine of the class described, the combination with a ticket issuing device adapted to issue tickets of different denominations; of operating means therefor; a locking mechanism for said operating means; coin receptacles; and manipulative means coöperating with the coins placed in the coin receptacles to determine the 30 denomination of the ticket to be issued and to render the locking mechanism for the operating means ineffective in order that the machine may be operated.

23. In a machine of the class described, 40 the combination with a ticket issuing device adapted to issue tickets of different denominations; of operating means therefor; a locking mechanism for said operating means; a series of coin receptacles; a single 45 key which when depressed coöperates with coins inserted into the coin receptacles to determine the denomination of the ticket to be issued and render the locking mechanism ineffective; and a locking device controlled 50 by said key to lock the key in its depressed position.

24. In a machine of the class described, the combination with a manipulative device; of a lever centrally pivoted to said device; 55 means normally rendering one end of said lever a pivotal center upon initial movement of said manipulative device; a detent given an invariable extent of movement by the initial movement of said manipulative 60 device; coin receptacles, the coins inserted into the same coöperating with said detent for moving said means normally rendering one end of the lever a pivoted center to permit continued movement of the manipulative device; and a latching device for said 65

manipulative device made operative upon the continued movement of said manipulative device to latch the latter in its operated position.

25. In a machine of the class described, 70 the combination with a ticket issuing device; of operating mechanism therefor; means normally preventing operation of said operating mechanism; coin receptacles; a single key coöperating with the coins inserted into 75 the receptacles to render said preventing means ineffective; a locking device controlled by said key for locking the key in depressed position; and connections intermediate said operating mechanism and said 80 key locking device for causing said locking device to release the key at the end of the operation of the machine.

26. In a machine of the class described, 85 the combination with a ticket printing and issuing device, adapted to issue tickets of different denominations, of operating means therefor, and coin receptacles for the reception of coins to control the operating means and to determine the denomination of the 90 ticket to be printed and issued by said device.

27. In a machine of the class described, 95 the combination with a ticket issuing device, adapted to issue tickets of different denominations, of operating means therefor, a normally effective locking device for said means, and coin receptacles for the reception of coins which control the rendering of the locking device ineffective and determine the denomination of the ticket to be issued.

28. In a machine of the class described, the combination with a printing mechanism, including a typecarrier to be differentially positioned, of manipulative means coöperating with coins inserted into the machine 105 to actuate differentially the typecarrier.

29. In a machine of the class described, the combination with a printing mechanism, including a typecarrier to be differentially positioned, of a single manipulative device 110 coöperating with coins of different values inserted into the machine to position differentially the typecarrier.

30. In a machine of the class described, the combination with an accounting device, 115 of a printing mechanism including a typecarrier, coin controlled mechanism, and connections between the coin controlled mechanism, the accounting device, and the printing mechanism whereby coins of different 120 values inserted into the machine determine the entering of amounts in the accounting device and the differential setting of the typecarrier of the printing mechanism.

31. In a machine of the class described, 125 the combination with a main operating mechanism, of a normally effective locking device therefor, a lever controlling the rendering of the locking device ineffective, a manipulative device, and two movable mem- 130

bers, moved by said manipulative device, and controlling the operation of said lever, one of said members being moved differentially under the control of coins inserted into the machine.

32. In a machine of the class described, the combination with a main operating mechanism, of a normally effective locking device therefor, a key for controlling the rendering ineffective of said locking device, and two members adapted to be connected by coins inserted into the machine and operated by a partial operation of said key to permit the complete operation of the key.

33. In a machine of the class described, the combination with a main operating mechanism, of a normally effective locking device therefor, a key for controlling the rendering ineffective of said locking device, two members adapted to be connected by coins inserted into the machine and operated by a partial operation of said key to permit the complete operation of the key, and means operated upon the complete operation of said key for locking the latter in operated position.

34. In a machine of the class described, the combination with a main operating mechanism, of a normally effective locking device therefor, a differentially movable member the extent of movement of which is controlled by coins inserted into the machine, and a manually operated lever adapted to be fulcrumed at different points, it being fulcrumed at one point to operate said member and at another point to render said locking device ineffective.

35. In a machine of the class described, the combination with a main operating mechanism, of a normally effective locking device therefor, a differentially movable member the extent of movement of which is controlled by coins inserted into the machine, a manipulative device, and a lever pivoted on said manipulative device, and adapted to be fulcrumed at different points during the depression of said key to move said member differentially and render said locking device ineffective.

36. In a machine of the class described, the combination with a lever, of a projection on said lever, a key for operating the lever, and two notched members normally locking said lever against operation, one of

said members being moved an invariable distance to bring the single notch of said member adjacent said projection, the other member being moved differentially under the control of coins to bring one of the plurality of its notches adjacent said projection whereby the lever is unlocked.

37. In a machine of the class described, the combination with a lever, of a projection on said lever, a key for operating the lever, and two notched members, operated by said key, and normally locking said lever against operation, one of said members being moved an invariable distance to bring the single notch of said member adjacent said projection, the other member being moved differentially under the control of coins to bring one of the plurality of its notches adjacent said projection whereby the lever is unlocked.

38. In a machine of the class described, the combination with a differentially movable member, of a main operating mechanism, a normally effective locking device for said mechanism, controlled by coins inserted into the machine, and means for moving the coins to control the extent of movement of said member and effect the operation of said locking device to release the machine.

39. In a machine of the class described, the combination with a differentially movable member, of a main operating mechanism, a normally effective locking device for said mechanism, controlled by coins inserted into the machine, and manipulative means for positively moving the coins to control the extent of movement of said member and effect the operation of said locking device to release the machine.

40. In a machine of the class described, the combination with a differentially movable member, of a normally inoperative operating mechanism, and a single manipulative device for moving coins inserted into the machine to render the operating mechanism operative and control the extent of movement of said member.

In testimony whereof I affix my signature in the presence of two witnesses.

FRANCESCO SKERI.
